UNITED STATES PATENT OFFICE

ANTHONY GERLOWSKI, OF CHICAGO, ILLINOIS, ASSIGNOR TO THE ROME COMPANY, INC., A CORPORATION OF NEW YORK

METHOD OF CONNECTING SPRINGS

Application filed July 29, 1929. Serial No. 382,059.

In the common form of bed spring the upper turns or coils of the large vertical springs are connected together by means of small crossed helical springs. Each helical 5 spring must be fastened at both ends to the vertical springs. Unless separate fastening elements are employed it is necessary to transform the wire at the end of each helical spring into the loop or eye. The manufacture 10 of the helical springs is a simple operation, requiring only the feeding of a wire through the machine and the automatic severing of the wire, after it has been shaped into helical form, to produce springs of the proper length. The old practice is then to 15 take up helical springs and form loops at the ends by inserting one end and then the other into suitable forming mechanism. The springs are then applied, by a separate manual operation, to the vertical springs in a spring cushion.

The object of the present invention is to make it possible to dispense with the two operations involving the inserting of first 20 one end of a spring, and then the other, into loop forming mechanism, and produce closed loops in the finished cushion without resorting to additional operations that are as costly as those which are eliminated. Or, if viewed 25 in another of its aspects, the present invention may be said to have for its object to make it possible to connect the crossed helical springs to the wires of the vertical springs of a spring cushion by means of closed eyes 30 or loops in such a manner that the cost of producing the structure as a whole will be less than has heretofore been the case for similar constructions.

The various features of novelty whereby 35 my invention is characterized will herein-after be pointed out with particularity in the claim; but, for a full understanding of my invention and of its objects and advantages, reference may be had to the following detailed description taken in connection with the accompanying drawing, wherein:

Figs. 1 and 2 are respectively a side elevation 40 and an end view of one of the small helical springs adapted to form part of a bed spring; Fig. 3 is a top plan view of a frag-

ment of the upper coil of one of the large vertical springs and the helical spring engaged therewith as a preliminary step to the forming of the eye or loop; Fig. 4 is an end or side view looking at the lefthand end of the part shown in Fig. 3, from the left; and Figs. 5 and 6 are views similar to Figs. 3 and 4, respectively, showing the completion of the loop or eye.

Referring to the drawing, 1 represents the wire of the upper turn or coil of one of the large vertical springs of a bed spring, and 2 is one of the small helical springs employed for tying together the large vertical springs. The helical spring is simply a plain helix whose end sections (of which only one is shown), are simply plain helical portions, indicated at 3, without being distorted or deformed. Consequently these springs may be made in a simple machine that automatically severs the wire whenever a predetermined number of coils have been made.

The helical spring is screwed upon the wire 1; being turned about its long axis through a comparatively small angle, only, 75 thereby carrying the free end past the outer side of the wire 1 and a short distance beyond the same as indicated in Fig. 4. If now a suitable clamping tool is applied, tending to press the end 3 down, as viewed in Fig. 4, and at the same time press up on the wire of spring 2 approximately 180 degrees removed from the free end, the end section of the helical spring will be transformed into a loop or eye 4. If, at the same 80 time the wire is pressed to form a loop or eye, a slight twist is given, the loop or eye will be caused to extend more or less in the direction of the length of the helical spring. The result is that the helical spring is fastened to the wire 1 by means of a closed loop 85 that will prevent accidental separation.

Any suitable means, pliers, for example, may be employed to form and set the eyes. I have found that pliers, forked to straddle 90 the wire of the vertical spring while the pliers are closing on the endmost half turn of the helical spring will give good results.

By my improved method I am enabled to dispense with the operations of preform-

ing eyes on the helical springs, taking the springs directly from the helix forming machine. Therefore, as it takes very little time to form and set the eyes as the helical springs are applied to the vertical springs, a saving in cost is effected over the old practice of pre-forming the eyes. Furthermore, the eyes made according to my method are closed; whereas preformed eyes that can be engaged with the vertical springs must necessarily be open, and must afterwards be closed if accidental separation of the helical springs from the vertical springs is to be guarded against.

15 While I have illustrated and described with particularity only a single preferred form of my invention, I do not desire to be limited to the exact structural details thus illustrated and described; but intend to cover 20 all forms and arrangements which come within the definitions of my invention constituting the appended claim.

I claim:

25 The method of making a connection between the wire of a spring and a small helical spring, which consists in screwing the free helical end of a helical spring upon the wire until said end passes a short distance beyond the wire on the side on which the 30 helical spring is located, and then pressing together the free end of the helical spring and the portion of the helical spring about 180 degrees distant therefrom to form a closed eye and twisting the eye to cause it to extend more or less in the direction of the 35 spring.

In testimony whereof, I sign this specification.

ANTHONY GERLOWSKI.
